UNITED STATES PATENT OFFICE.

CHARLES MUNTER, OF NEW YORK, N. Y.

COMBINED ABDOMINAL SUPPORT AND SHOULDER-BRACE.

1,367,421.

Specification of Letters Patent.

Patented Feb. 1, 1921.

Original application filed December 5, 1917, Serial No. 205,627. Divided and this application filed January 14, 1920. Serial No. 351,390.

To all whom it may concern:

Be it known that I, CHARLES MUNTER, a citizen of the United States, residing at New York city, borough of Manhattan, county 5 and State of New York, have invented a certain new and useful Combined Abdominal Support and Shoulder-Brace, of which the following is a specification.

This application is a division of my co-pending application S. N. 205,627, filed Dec. 5, 1917, being specific to the form shown in Figure 4 of that case, and the invention herein disclosed is a combined abdominal support and shoulder brace adapted 10 to be worn by both men and women to serve the purpose of properly sustaining the abdomen, forcing the shoulders back into proper position and to lend correct curvature to the spine for the purpose of stimulating proper respiration and correct carriage.

The object of the present invention is to provide a combined support and shoulder brace which will efficiently carry out its purposes through the employment of a simple garment structure so constituted that both the shoulder brace and abdominal supporting portions thereof may be simultaneously adjusted while in position on the wearer to 15 support the body in correct, anatomical poise.

In the preferred embodiment of the invention, the garment is so constructed that the act of securing a belt about the waist line 20 serves to simultaneously adjust all portions of the garment to the proper dimensions.

Features of the invention, other than those specified, will be apparent from the hereinafter detailed description of the drawings taken in conjunction with the accompanying drawings.

In the accompanying drawings, I have illustrated one practical embodiment of the invention, but the construction therein shown is to be understood as illustrative only, and not as defining the limits of the invention.

Fig. 1 is a rear elevation of a garment embodying the present invention in place on the wearer.

Fig. 2 is a side elevation of the showing of Fig. 1; and,

Fig. 3 shows a garment laid out flat. In constructing the garment of this in-

vention, the same may be either made from 55 a single piece of material, properly cut to shape and provided with a binding around the edge thereof, or it may be built up from a plurality of pieces sewed together to lend correct contour thereto. The garment embodies 60 a back member A substantially equal in width to the back of the body of the wearer and of such height as to extend very slightly below the waist to the shoulders thereof, and two side portions B, B' which 65 are secured at their upper portions to the back member by shoulder portions C, C' as shown in Fig. 3. The side members B and B' are otherwise free from the back member A so as to provide openings a, a' 70 which are adapted to extend downwardly from the arm holes c, c' to the lower edge of the garment and at the sides thereof.

When the garment is in position on the wearer as shown in Figs. 1 and 2, the free 75 edges of the side portions B and B' are adapted to be secured together in any suitable manner, but, in practice, this is preferably accomplished by cooperating snap fasteners d, d', positioned, respectively, 80 along the corresponding edges of each of said side portions. The snap fasteners provide a simple and efficient method of securing the front edges of the garment together in such manner that the garment may be 85 readily put on or removed from the body. The adjustment of the garment to the wearer is obtained through adjustment of the side openings a and a' and to this end such openings are provided with suitable 90 lacing which, in the preferred embodiment of the invention, is of the belt operated type. The belt operated lacing may be associated with the side openings in various ways but, for the purpose of illustration, I have shown 95 a row of eyelets e positioned in the back portion A along the edge of the opening a, and a similar row of eyelets e' positioned in said back portion along the edge of the opening a'. To the opposite edges of the 100 corresponding openings are secured the ends of laces E and E' which extend across the openings and through the juxtaposed eyelets e and e'. The free ends of the laces E and E' are brought together and secured to 105 belt sections F and F', respectively, the former of which is provided with a buckle f as shown in Fig. 3.

When the garment is in position on the wearer, the belt sections F and F' may be brought into coöperative relation and pulled taut for the purpose of simultaneously adjusting all of the laces and by so doing bring about correct contour of the entire garment.

A distinct advantage of the garment of this invention resides in the fact that it may be adjusted by the wearer to properly suit his needs while it is in place upon his figure, and that the entire garment may be adjusted by simply pulling the belt sections tight and securing them in position about the body. This is due to the fact that the side openings extend through both the shoulder brace and abdominal supporting portions of the garment, and in this regard it will be manifest that the garment is, theoretically speaking, formed of two portions, a lower abdominal supporting portion and an upper shoulder supporting portion, although these two portions are so associated that a part of one serves as a part of the other in either instance. In practice, the garment may be provided with additional openings and suitable associated lacings and may be further ribbed or stiffened without departing from the spirit of the invention.

The mode of operation of the garment, as well as the manner in which it serves to perform its functions will be clearly understood from the foregoing description. It will be manifest, that in donning the garment the arms of the wearer are slipped through the arm holes c and c' to bring the garment into a position wherein the back portion A will overlie the back of the wearer and the shoulder portions C and C' extend over his shoulders. The side portions B and B' are next wrapped about the figure and the snap fasteners d, d' brought into coöperation to close the open front. The belt portions F and F' are thereafter buckled together to bring about proper adjustment of the side openings a and a'. The garment is manufactured in different sizes and the parts are so proportioned in each garment that, when a garment is worn upon a figure of corresponding size, the fit will be correct in every detail. Moreover, the garment is so constructed as to cover as little of the figure as it possibly can cover with the proper carrying out of its functions. The side portions B and B' are made of sufficient width so as to not cut into the body and the back portion extends substantially the entire height of the back of the wearer, so that when the garment is in adjustment the back is supported for substantially its full extent and the abdomen is supported for substantially its full extent. The garment causes the spinal column to partake of its proper curvature and proper respiration and carriage will result.

Having thus fully described the inven-

tion, what I claim as new and desire to secure by Letters Patent is:

1. As a new article of manufacture, a garment embodying a shoulder brace portion adapted to overlie the back of the wearer and provided with shoulder members forming arm holes, in combination with an abdominal supporting portion adapted to overlie the abdomen of the wearer, said garment being provided with openings extending downwardly from the arm holes to the lower edge of the garment, lacings associated with the openings, and belt sections associated with the lacings, whereby tension placed on the belt sections is transmitted to the lacings and the side openings adjusted to simultaneously adjust both the shoulder brace and abdominal supporting portions. 75

2. As a new article of manufacture, a garment embodying a shoulder brace portion adapted to overlie the back of the wearer, and provided with shoulder members forming arm holes, in combination with an abdominal supporting portion connected to the opposite sides of said shoulder brace portion and adapted to overlie the abdomen of the wearer, said garment being provided with openings extending downwardly from the arm holes to the lower edge of the garment, and lacings associated with said openings and capable of adjusting the openings to simultaneously adjust both shoulder brace and abdominal supporting portions. 90

3. As a new article of manufacture, a garment embodying a solid back portion adapted to overlie substantially the entire back of the wearer, front portions adapted to overlie the abdomen and connected to the back member by shoulder members secured to the front and back members and passing over the shoulders of the wearer, whereby adjustable openings are provided between the lateral edges of the back member and the adjacent edges of the front members, adjustable lacings associated with the openings, and a belt section coöperating with the lacings of each opening. 100

4. As a new article of manufacture, a garment embodying a solid back portion adapted to overlie substantially the entire back of the wearer, front portions adapted to overlie the abdomen and connected to the back member by shoulder members secured to the front and back members and passing over the shoulders of the wearer, whereby adjustable openings are provided between the lateral edges of the back member and the adjacent edges of the front members, and adjustable lacings associated with each opening. 115

5. As a new article of manufacture, a garment embodying a back portion adapted to overlie the back of the wearer, front portions adapted to overlie the abdomen, said front members being cut away above the 120

abdomen, whereby the front of the body above the abdomen is uncovered, and being connected to the back member by shoulder members secured to the front and back members 5 and passing over the shoulders of the wearer whereby adjustable openings are provided between the lateral edges of the back and front members, adjustable lacings associated with each opening, and means 10 whereby the lacings may be adjusted while the garment is being worn to simultaneously adjust the garment both at the shoulders and at the abdomen.

6. As a new article of manufacture, a 15 combined abdominal support and shoulder brace comprising a back member adapted

to overlie the back of the wearer, front members adapted to overlie the abdomen and to be detachably connected together at the front, shoulder straps adapted to extend 20 over the shoulders and serving to connect the front and back members, said front and back members being adjustably connected along their lateral edges at the sides from the arm pits to below the waist line, and 25 means for simultaneously adjusting said members while upon the wearer and to thereby adjust both the shoulder brace and the abdominal support.

In testimony whereof I have signed my 30 name to this specification.

CHARLES MUNTER.
